US0D1036978S

(12) **United States Design Patent** (10) **Patent No.:** **US D1,036,978 S**
(45) **Date of Patent:** **** Jul. 30, 2024**

(54) **FOOT REST**

(71) Applicant: **Posturewise Pty Ltd**, Kensington (AU)

(72) Inventor: **Ryan Malcolm Lamp**, Kensington (AU)

(73) Assignee: **POSTUREWISE PTY LTD**, Kinsington (AU)

(**) Term: **15 Years**

(21) Appl. No.: **29/828,281**

(22) Filed: **Feb. 25, 2022**

(30) **Foreign Application Priority Data**

Aug. 25, 2021 (AU) 202115066

(51) **LOC (14) Cl.** **08-11**

(74) *Attorney, Agent, or Firm* — Kevin J. McNeely, Esq.; McNeely, Hare & War, LLP

(57) **CLAIM**

The ornamental design for a foot rest, as shown and described.

DESCRIPTION

FIG. 1 is a Top Perspective View showing my new design; FIG. 2 is a Bottom Perspective View thereof;

FIG. 3 is a Top View thereof;

FIG. 4 is a Bottom View thereof;

FIG. 5 is a Front View thereof;

FIG. 6 is a Rear View thereof;

FIG. 7 is a Side View thereof; and,

FIG. 8 is an Opposite Side View thereof.

The broken lines in the drawings illustrate portions of the foot rest and form no part of the claimed design.

1 Claim, 4 Drawing Sheets
